UNITED STATES PATENT OFFICE

WINFRED S. GRIFFITH, OF WORCESTER, MASSACHUSETTS, ASSIGNOR TO GRATON & KNIGHT COMPANY, OF WORCESTER, MASSACHUSETTS, A CORPORATION OF MASSACHUSETTS

METHOD OF PREPARING LEATHER BELTING FOR GLUING OR CEMENTING

Application filed May 14, 1928. Serial No. 277,751.

This invention relates to a method of preparing leather belting to receive glue or cement, particularly in the manufacture of double belting. It is essential that all of the 5 fleshy material be removed from the belt and that the entire fleshy side of the belt be uniformly roughened before the cementing material is applied. This work has been heretofore commonly performed by the use of hand 10 scrapers and by the use of hand brushes or cards, a very laborious operation.

It is the object of my invention to provide an improved and novel process of preparing belts for cementing in which process the 15 leather is subjected to a series of scratching, skiving and brushing operations, which may be much more rapidly and economically performed than the old method above set forth.

In the preferred method of practicing my 20 invention I also provide for reducing the laps in the belt to uniform thickness in addition to removing the flesh and brushing the surface.

My invention further relates to the sequence of operations hereinafter set forth 25 and more particularly pointed out in the appended claims.

Mechanism suitable for the practicing of my invention is shown in the drawings in 30 which

Fig. 1 is a sectional end elevation of a scratching machine for performing the first step in my improved method;

Fig. 2 is a detail perspective view of a 35 portion of a belt after the scratching operation has been performed;

Fig. 3 is a sectional end elevation of a skiving machine for reducing the laps to uniform thickness;

Fig. 4 is a partial perspective view of a 40 portion of the belt after the skiving of the lap has been performed;

Fig. 5 is a sectional end elevation of a second skiving machine adapted for removing 45 the fleshy material which has been raised on the surface of the belt by the scratching machine;

Fig. 6 is a detail perspective view of a portion of the belt after the fleshy material has 50 been removed therefrom;

Fig. 7 is a perspective view of a portion of an inspecting table over which the belt preferably passes for purposes to be described, and

Fig. 8 is a sectional end elevation of a second scratching or brushing machine by which the flesh side of the belt is given a uniformly roughened or brushed surface.

Referring first to Fig. 1, I have indicated a skiving machine comprising a frame 10 in which a feed roll 11 is rotatably mounted. A second roll 12 is freely rotatable in bearing blocks 13 above the feed roll 12. The blocks 13 may be raised or lowered by adjusting nuts 14 on studs 15, mounted in the bearing blocks 13 and the blocks 13 are held yielding- 60 downward by springs 16. The feed roll 11 preferably has a leather covering 17 and the feed roll 12 preferably has a rubber covering 18. 65

A brushing or scratching roll 20 is mounted on a shaft 21, rotatable in bearings in the frame 10, and is preferably provided with a peripheral covering 22 of card clothing. The shaft 21 and roll 20 are rotated at high 70 speed in the direction of belt travel, and the feed roll 11 is driven from the shaft 21 at relatively slow speed. 75

A series of presser fingers 23 are mounted on a cross rod 24 supported in brackets 25, 80 which are secured to a cross bar 26 and are positioned by bolts 27, fixed in said cross bar and extending through a fixed bearing 28 in the frame of the machine.

Springs 30 encircle the bolts 27 and move 85 the cross bar 26 and brackets 25 as far to the right in Fig. 1 as is permitted by the wing nuts 29 on the bolts 27.

The fingers 23 are limited in downward movement by the heads of screws 33 threaded into the cross bar 26 and the fingers 23 are held in yielding contact with the heads of the screws 33 by springs 35 mounted in said screws. Hardened steel discs 36 are preferably mounted in the lower faces of the presser 90 fingers 23, to form contact members for the upper or grain face of the belt B. Front and rear supporting tables 37 and 38 are provided for guiding the belt through the machine. 95

As the belt is fed slowly through the ma- 100

chine by the feed rolls 11 and 12, the rapidly rotating card clothing on the scratching roll 20 tears up the soft fleshy material remaining on the flesh side of the belt and causes it to stand out loosely from the lower face of the belt.

The belt B then passes to a skiving machine (Fig. 3) comprising a table 40, a fixed knife 41, a presser roll 42 having bearing portions 43 rotatable in eccentric openings in discs 44, provided with gear teeth 45 on their periphery.

The teeth 45 are engaged by an idle gear 46 which in turn is actuated by a gear 47 mounted on a shaft 48 having a handle 49 secured thereto. The roll 42 is preferably covered with a substantial thickness of soft rubber.

The eccentric bearing member 44 has an upwardly projecting portion 50 to which a spring 51 is attached, which will restore the roll 42 to raised position as soon as the handle 49 is released. As the belt B is drawn along over the table 40 and over the skiving knife 41, the soft rubber roll 42 engages the upper surface of the belt and is available to press the same yieldingly downward.

Whenever a splice in the belt approaches, it is necessary to apply pressure to the belt to skive the lap, which is accomplished by manually rotating the eccentric bearing 44 by means of the handle 49, thus lowering the presser roll 42 and placing sufficient pressure on the belt to cause the leather to be skived off to substantially uniform thickness, as indicated in Fig. 4.

A second skiving machine (Fig. 5) may be positioned adjacent but beyond the skiving machine above described, and this second machine comprises a table 52 having a skiving knife 53 mounted therein and a presser roll 54 mounted in vertically slideable bearings 55 and held yieldingly downward by coil springs 56. As the belt B passes under the presser roll 54 it is pressed downward, bringing the roughened fleshy material into contact with the knife 53 which shaves or skives the projecting fleshy portions from the lower face of the belt.

Under some circumstances, the second skiving roll and knife may be omitted and both operations of skiving the laps and removing the fleshy material may be performed by the single skiving mechanism shown in Fig. 3, the operator varying the pressure as necessary. It is considered preferable, however, to use the second skiving machine indicated in Fig. 5, leaving the mechanism shown in Fig. 3 for evening the laps and setting the second mechanism permanently at the right adjustment for skiving off the fleshy material.

After the belt B leaves the skiving machine in the condition indicated in Fig. 6, it preferably passes over an inspecting table 60 (Fig.

7) to a second scratching machine (Fig. 8), which is substantially identical in all respects to the machine shown in Fig. 1, but which is set to apply a very light pressure to the belt, by which the belt is merely uniformly roughened or brushed by card clothing 62 mounted therein.

The inspection table 60 is provided not only for inspection but also to permit scraping and removal manually of any fleshy material which might, through some deficiency in operation, get past the scratching and skiving machines.

In actual operation, the belt is frequently looped, so that it will pass twice in succession through one or more of the different machines.

Having described forms of mechanism suitable for carrying out my improved operation, the method is as follows:

The belt is introduced between the feed rolls 11 and 12 of the first scratching machine, as indicated in Fig. 1 and the card clothing 22 tears up the soft fleshy material and causes it to stand out from the lower face of the belt. The independent presser fingers cause all portions of the belt to be pressed yieldingly and uniformly against the brushing or scratching cylinder, regardless of variations in the thickness of the belt.

The belt then passes through the skiving machine, which may be set to skive off the fleshy material and which is provided with means for lowering the presser roll to exert increased pressure on the belt as a lap is drawn over the knife 41. Instead of using the knife 41 and roll 42 for both skiving off the fleshy material and also for evening the laps, I may use this mechanism for the latter purpose only, providing a second skiving mechanism as above described for skiving off the fleshy material as indicated in Fig. 5.

The belt is then drawn over the inspection table 60, permitting manual removal of any fleshy material escaping the operation of the scratching and skiving mechanisms, and the belt then passes through the second scratching machine, which is set to exert very light pressure on the belt, thus causing the belt to be lightly brushed or scratched over its entire surface and thus placing it in a satisfactory condition to receive glue or cement.

Having thus described the several steps of my improved process, together with certain forms of mechanism by which the process may be carried out, I do not wish to be limited to the details herein disclosed otherwise than as set forth in the claims, but what I claim is:

1. The method of preparing belts for gluing or cementing which consists in causing the fleshy material on the belt to extend loosely therefrom, cutting off said projecting fleshy material, and thereafter uniformly roughening the flesh side of the belt.

2. The method of preparing belts for gluing or cementing which consists in scratching the flesh side of the belt to cause the fleshy material on the belt to extend loosely therefrom, skiving off said projecting fleshy material, and thereafter uniformly roughening the skived surface of the belt.

3. The method of preparing belts for gluing or cementing which consists in scratching the flesh side of the belt to cause the fleshy material on the belt to extend loosely therefrom, skiving off said projecting fleshy material, and thereafter lightly scratching the skived surface of the belt to uniformly roughen the same.

4. The method of preparing belts for gluing or cementing which consists in scratching the flesh side of the belt to cause the fleshy material on the belt to extend loosely therefrom, skiving off said projecting fleshy material, skiving the laps of the belt under increased pressure, and thereafter lightly scratching the skived surface of the belt to roughen the same.

5. The method of preparing belts for gluing or cementing which consists in scratching the flesh side of the belt to cause the fleshy material on the belt to extend loosely therefrom, skiving off said projecting fleshy material, manually removing any fleshy material remaining thereon, and thereafter uniformly roughening the skived surface of the belt.

In testimony whereof I have hereunto affixed my signature.

WINFRED S. GRIFFITH.
